UNITED STATES PATENT OFFICE.

FRANK EDWIN CABANIS, OF PLATTEVILLE, WISCONSIN.

DISPLAY-BOX FOR FRUITS AND VEGETABLES.

No. 904,404.

Specification of Letters Patent.

Patented Nov. 17, 1908.

Application filed March 23, 1908. Serial No. 422,667.

To all whom it may concern:

Be it known that I, FRANK EDWIN CABANIS, a citizen of the United States, and a resident of Platteville, Grant county, Wisconsin, have invented an Improvement in Improved Display-Boxes for Fruits and Vegetables, of which the following is a specification.

My invention is in the nature of a skeleton guard for boxes or other receptacles for fruits and vegetables, and other articles. The guard is so constructed that it is extensible lengthwise and thus adapted for boxes of different lengths, and it is also adjustable outward, or at different angles to the open side of the box or receptacle.

The details of construction, arrangement, and combination of parts embodying my invention, are as hereinafter described and illustrated in the accompanying drawing, in which

Figure 1 is a perspective view of a double, or two-compartment, box provided with my improved guard. Fig. 2 is an enlarged perspective view of a portion of the guard.

The box 1 is shown provided with two compartments whose open side is at the front. The guard is composed of a series of longitudinal rods or bars 2, and side plates 3, the latter being essentially triangular in form and pivoted to the lower front corners of the box and arranged parallel to the lower ends of the same, and, therefore, at right angles to the longitudinal bars or rods 2. The side plates 3 are provided in their upper portions with arc slots 4 which receive headed studs or pins 5 that are fixed in the ends of the box exteriorly, and close to the front edge. Screw-nuts 6 are applied to these studs or pins, which are threaded correspondingly. It is apparent from this construction and combination of parts, that the plates may be turned on their pivots and thrown inward or outward, as required to place the skeleton portion of the guard at a greater or less inclination to the front of the box 1, and that the plates 3 may be clamped in any inclination or adjustment, by means of the nuts 6. Thus, the skeleton portion of the guard may be placed parallel to the front of the box, or at a vertical inclination thereto, as may be required to more freely display the contents of the box. The outer ends of the rods 2 are connected with the plates 3 by slitting and bending over the outer edges of the plates. In other words, by slotting

or notching the front edges of the plates and bending in the intervening portions, eyes are formed which serve to receive the looped ends of the rods or bars 2. It is to be understood, however, that the connection between the parts 2, 3, may be made in any other convenient or preferred manner.

In order to adapt the guard for boxes of different lengths, the bars 2 are made extensible. As a cheap and convenient construction to provide for this function, the inner ends of the rods or bars 2, may be curved transversely to form eyes which receive the opposite rods or bars, the two parts being thus adapted to slide telescopically on each other, as will be readily understood from the drawing. The pivots 7 of the end plates 3 are preferably formed of screws and thus the entire guard is adapted to be readily applied to or detached from any box.

It will be seen that the end plates 3 are adapted by reason of the joint between them and the rods 2, to fold against the inner sides of the rods so as to lie flat or parallel thereto. This feature and the adaptation of the rods to slide on each other, enables the guard to be folded or contracted to a very small compass so that it may be transported or stored with greater facility.

I provide a form of central support for the wires 2, which is particularly needed when the latter are of unusual length. The support comprises a rod 8 whose ends are looped about the upper and lower wires, and a chain 9 which is attached to the upper loop of said rod and detachably connected with a hook which is fixed in the central partition of the box 1. The rod 8 lies outside the wires intervening the top and bottom one and thus supports all the wires against outward pressure. It is obvious that the chain 9 may be taken up or let out as required to accommodate the different vertical inclinations at which the attachment may be placed.

What I claim is:

1. The combination with a box having an open front, of a skeleton guard comprising end plates which are pivoted and adapted for adjustment at their outer ends forward and back, and bars arranged parallel and connecting such end portions, substantially as described.

2. The combination with a box having an open front, of a guard therefor, comprising end portions which are pivoted at their lower ends and means for securing the upper ends

- of the same adjustably, and a series of rods or bars which are extensible in length, whereby the guard is adapted for boxes of different lengths, substantially as described.
- 5 3. The improved guard comprising a body portion which is extensible, and end portions adapted for adjustment on the ends of a box and suitably connected with the body portion, substantially as described.
- 10 4. The improved guard for the purpose specified, comprising a body portion formed of rods which are telescopically connected, and end plates with which said rods are also connected, the same being adapted for attachment to the ends of a box, substantially as described.
- 15 5. The improved guard comprising a series of bars which are slid able on each other, and end plates jointed with the ends of said bars and adapted to fold inward against the same, so as to lie parallel thereto, as shown and described.
- 20
6. The combination with a box having an open front and a guard applied thereto and consisting of end pieces adapted for attachment to the ends of the box, and a series of wires connecting such pieces, of a central support consisting of a rod attached to the wires and extending outside thereof, a chain connected with the upper end of the rod and a device fixed to the box with which such chain engages, detachably, substantially as described. 25
7. The improved guard comprising a body portion, and end plates which are hinged thereto at their outer edges and adapted to fold against the body portion so as to lie flat or parallel thereto, as shown and described. 30 35

FRANK EDWIN CABANIS.
